UNITED STATES PATENT OFFICE.

JACOB W. BARD, OF SPRINGFIELD, ILLINOIS, ASSIGNOR TO SANGAMO ELECTRIC COMPANY, OF SPRINGFIELD, ILLINOIS, A CORPORATION OF ILLINOIS.

THERMO-COUPLE.

1,221,270.

Specification of Letters Patent.

Patented Apr. 3, 1917.

Application filed January 30, 1914. Serial No. 815,425.

To all whom it may concern:

- Be it known that I, JACOB W. BARD, a citizen of the United States, residing at Springfield, in the county of Sangamon and 5 State of Illinois, have invented certain new and useful Improvements in Thermo-Couples, of which the following is a specification, reference being had to the accompanying drawings.
- 10 My invention relates to thermo-couples, and has for its object to provide a new and improved thermo-couple especially suited for use in connection with certain electrical instruments, such as mercury motor meters, 15 such improvements relating more particularly to the construction of what may be termed the "frame" of the thermo-couple, and the devices for connecting up the thermo-couple so as to vary the manner in 20 which the current generated is distributed. I accomplish my object as illustrated in the accompanying drawings and as hereinafter described. What I regard as new is set forth in the claims.
- 25 In the drawing,—
- The figure is a perspective view of the thermo-couple, the heating coil being omitted.
- Referring to the drawings,—
- 30 39 indicates the thermo-couple, which comprises two plates 40—41 of suitable dissimilar metals, such as a plate of copper and a plate of suitable alloy, said plates being soldered together at one end as shown at 42.
- 35 Said plates are bent to form an open loop or approximately C-shaped figure of a general rectangular outline, their opposite ends being separated and being provided with parallel ears 43—44, respectively, having 40 notches 45—46 in their upper ends. The plates 40—41 are of reduced cross-section adjacent to their connected ends as shown in the drawing, in which said plates are shown as provided with notches or indentations 47 in their upper and lower margins. The object of thus reducing the cross-sectional area 45 of the thermo-couple members is to impede the conduction of heat from the joined ends of said members toward their separated 50 ends. The joined ends of the members

40—41 may be heated in any suitable way, but I prefer to employ for that purpose a high resistance coil wound upon the joined ends of said plates, the effect of which is to heat such joined ends when a current passes 55 through said coil, and as the maximum effect of a thermo-couple is secured by maintaining as great a difference as possible between the temperature of the joined ends of its members and that of its separated 60 ends, by reducing the cross-sectional area of the members composing the couple, the escape of heat by the conductivity of the materials composing the members is reduced 65 to a minimum, and consequently the desired difference in temperature is maintained.

The ears 43—44 of the thermo-couple are adapted to be connected to suitable contact blocks, such, for example, as those shown and described in my application for Patent 70 Ser. No. 32,656, filed June 7, 1915. Said ears constitute, respectively, the positive and negative terminals of the thermo-couple and provide convenient means for attaching the same to the parts with which it is to be connected. I thus provide a very efficient thermo-couple which is light, compact and durable, and which may be easily applied to or removed from the parts with which it is to coöperate.

80 What I claim as my invention, and desire to secure by Letters Patent, is,—

1. A thermo-couple, comprising two dissimilar integral metallic members joined together at one end, each of said members being notched to reduce its cross-sectional area intermediate the point of their juncture and its opposite end.

2. A thermo-couple, comprising flat integral strips of dissimilar metals joined together at one end and fashioned into an approximately open loop, each of said strips being notched to reduce its cross-sectional area intermediate the point of their juncture and its opposite end.

JACOB W. BARD.
